JOHN RUHL AND ELIAL S. HERRINGTON, OF DEFIANCE, OHIO.

Letters Patent No. 78,186, dated May 19, 1868.

IMPROVEMENT IN HAY-RAKERS AND LOADERS.

The Schedule referred to in these Letters Patent and making part of the same.

TO ALL WHOM IT MAY CONCERN:

Be it known that we, JOHN RUHL and ELIAL S. HERRINGTON, of Defiance, in the county of Defiance, and State of Ohio, have invented certain new and useful Improvements in Self-Raking and Loading Hay-Wagon; and we do hereby declare that the following is a full, clear, and exact description thereof, reference being had to the accompanying drawings, and to the letters of reference marked thereon, which form a part of this specification, in which—

Figure 1 represents a side elevation,

Figure 2 a plan view, and

Figure 3 a plan view of the belt-attachment with the raking-attachment removed.

The nature of this invention consists in constructing a wagon-body with a hay-loading apparatus, substantially in the manner hereinafter set forth.

To enable others skilled in the art to make and use my invention, I will now describe its construction and operation.

A represents a wagon-body, and B B the wheels. C designates the bounds attached to the axle of the fore wheels. D represents the tongue, which can be turned back under the wagon-body when desired. E E designate two standards or uprights attached to opposite sides of the body A, and firmly held together by means of boards f f and cap-piece g. h h designate two rails or supports secured to the hinder part of the body A, as shown in fig. 1. The object of these rails is to support the hay-loading and gathering device. k k represent two braces extending from the top of the uprights E E, to which they are fastened at a suitable distance below the rails h h, and firmly bolted to said rails or supports. To the lower ends of braces k k is secured one of the axles upon which work the cylinder M and hind wheels B B. N represents a lever, having its fulcrum in rail h. The object of this lever is to operate the slide m, as will be more fully apparent hereafter. The slide m is confined by means of guides s s, and furnished at its outer end with a slot through which one end of the rod L passes. t represents a stop designed to hold the lever in position when the rake-teeth are in or out of use. i i represent a series of slats, secured at their upper ends to the braces a a, by means of a metal rod, said rod passing through the slats i i, with their outer ends resting in perforations in braces a a. These slats are fastened together in couples by two sets of clamps, as seen in fig. 2, and provided at their lower ends with teeth j j. L designates a bar placed a little above and at right angles with the rails or supports h h. p represents a metal rod, which passes through the rails h h, and having its ends bent upward, so that they will pass through the ends of bar L and slide m, and thus allow said bar to be operated when desired. V designates a number of curved metal rods, the lower ends of which are fastened to bar L, and the upper end of each is secured to the clamp which binds each set of slats together. The slide m, it will be observed, is secured at its outer end to bar L; so that, by the action of the lever N, the bar L can be thrown outward or inward, as the case may require. R represents a cylinder pivoted to the upper ends of braces k k. F designates an endless belt, which passes around the cylinders M and R. At a proper distance apart, the slats o o are fastened laterally on the outer surface of belt F. Said slats are furnished with teeth, for the purpose of taking up the hay when the belt is in motion.

The operation of my machine is as follows: When the wheels are in motion, and the slats i i are in position, the front ends of teeth j j will be directly under cylinder M, and as the cylinder rotates and gives motion to the belt F, the teeth on the slats o o will take up the hay when gathered by the teeth j j, and carry it up over the cylinder R, from whence it will drop into the wagon-body. When the machine is to be moved from one part of the field to another, the teeth j j can be elevated out of the way by the action of the lever N.

What we claim as new, and desire to secure by Letters Patent, is—

The lever N, slide m, bar L, and rod p, combined, as and for the purpose set forth.

In testimony that we claim the foregoing as our own, we affix our signatures in presence of two witnesses.

JOHN RUHL,
ELIAL S. HERRINGTON.

Witnesses:

JOSIAH Z. HILL,
S. F. SUTPHEN.
